UNITED STATES PATENT OFFICE.

WILLARD D. RICHARDSON, OF HEBRON, NORTH DAKOTA.

SCREENING APPARATUS.

1,282,127.

Specification of Letters Patent. Patented Oct. 22, 1918.

Application filed June 10, 1916. Serial No. 102,817.

To all whom it may concern:

Be it known that I, WILLARD D. RICHARDSON, a citizen of the United States of America, residing at Hebron, in the county 5 of Morton and State of North Dakota, have invented certain new and useful Improvements in Screening Apparatus, of which the following is a specification.

My invention relates to screening apparatus and has to do particularly with that 10 class of screening or separating machine composed of cloth and stretched and fastened upon steel frames and in which the screen is jarred and vibrated by percussive 15 action or impact upon the reinforced screen cloth or frame. My aim is to provide mechanism which is readily accessible for cleaning and repairing and which, at the same time, is capable of performing all of 20 the steps of screening efficiently and with a minimum number of elements.

One of the important features of my invention arises from the fact that I utilize, in combination with one or more fine meshed 25 screens, a scalping screen which protects the fine meshed screens from the coarser particles of the material; is of such nature and so disposed that the fine meshed screens are readily accessible, and which renders an independent conveyer element unnecessary. Frequent cleaning is necessary in screens of 30 this type, particularly in cold weather when plastic materials are being operated upon and my screen structure is peculiarly desirable in that the scalping screen does not interfere with direct access to the finer screens.

Another important feature of my invention resides in the fact that my feeding and scalping screen is so located and supplemented that it may distribute the partially screened material to both sides or either side of a central line, which central line forms the apex of adjacent downwardly inclined screens. The regulating mechanism comprising a part of my invention makes possible the regulable control of the amount of material to be fed to either of these screens and may be so adjusted that one screen only is operated, it being understood that 45 one of these downwardly inclined screens may be entirely dispensed with.

One of the important features of my invention has to do with a novel vibrating mechanism for the inclined screen structure, 50 whether this inclined screen structure com-

prises a single screen or multiple superposed screens. This peculiar vibrating mechanism is simple and effective in that it delivers series of light rapid blows upon the upper sides of the screens, giving the intense vibration of the screen cloth required for large capacity and to prevent clogging of the mesh and yet leaves the covers of the screen structure unencumbered and free from weighty apparatus.

The preferred embodiment of my invention is shown in the accompanying drawings wherein similar characters of reference designate corresponding parts wherein:

Figure 1 is a front elevation of my improved apparatus.

Fig. 2 is a side elevation of the structure shown in Fig. 1.

Fig. 3 is a detail, in cross section, of the vibrating mechanism desirably utilized by me.

In the drawings there is shown a rotating scalping screen 1 decreasing in diameter from the right to left of Fig. 1 and designed to be fed from left, being turned by a pulley 2. As shown best in Fig. 2, the rotatable scalping screen is mounted at the apex of a pyramid formed by two screen members 3 and 4 which incline downwardly and outwardly from the said scalping screen and which are designed to be fed thereby. The scalping screen is preferably located within a hopperlike structure 5 having a funnel chute 6 and a central gate 7 adjustable to varying positions as indicated in Fig. 2 and provided with means for locking in adjusted position. This means may take the form of an arcuate slot 8 from which a threaded pin 9 extends for the reception of a clamping nut 10.

The screen elements 3 and 4 may be of duplicate structure and each comprises a sharply inclined chute 11, a comparatively fine screen 12 and a top cover 13. For successful screening with a screen of this type, it is necessary that any vibrating action result initially from blows applied to the upper side of the screen. Prior devices have accomplished this but the vibrator elements used have been mounted upon the cover of the screening elements and have produced certain material drawbacks which are obviated by my invention.

The particular form of vibrating mechanism used by me is illustrated in Fig. 2 and,

in detail, in Fig. 3. It comprises a series of 5 vibrator elements which are actuated from beneath the screen by successively operating cams 14 simultaneously driven by belts 15 and continuously actuating vibrator elements. In Fig. 2 it will appear that the cams of both screening elements are operated from one driving mechanism and that the uppermost vibrators of both screens are 10 desirably actuated from the cams of one shaft 16.

The preferable structure of each vibrator is shown best in Fig. 3 and comprises an inner pipe 17 bifurcated at its lower end for 15 the reception of a roller 18. It will be understood that this pipe may be replaced by a solid rod but that in the present instance it is formed of a lower part and an upper part connected by the sleeve 19 into which they 20 are passed. The upper part is held in place by a set screw 20 while the lower part is threaded and prevented from rotating by a set screw 21. The pipe or rod 17 extends upwardly through the bottom of chute, the 25 screen, and the cover of the screening element and carries a hammering head 22 which is in the form of an annulus threaded onto the pipe 23 and having its upper edge rounded as at 24. By loosening the upper set 30 screw 20 the upper section of the pipe with hammer can be lifted out when necessary.

The sleeve 19 is formed at its upper end with an L-shaped flange structure 25 within which rests a coil spring 26 designed to bear 35 at its upper end against the reinforcing structure 27 connected to the bottom 11 of the chute. On the upper surface of this bottom, there is a socket structure 28 into which the pipe casing 29 is threaded. This sleeve or 40 pipe casing 29 concentrically surrounds the pipe or rod 17 and has a collar 30 adjustably threaded upon its upper end for the support of a coil spring 31 whose upper end in turn bears against the screen 12.

45 On the upper surface of the screen 12 is a second socket 33 which receives the pipe 32. This pipe has a collar 35 threaded upon its upper end having an L-shaped flange structure 36 containing a wooden anvil 50 block 37. This L-shaped flange structure is rounded at its surface to permit raising or lowering of the cover 13 without interference, this cover 13 being provided with apertures 38 for each vibrator.

55 In operation, material to be screened is fed into the smaller end of the revolving screen and the rotation of this revolving screen together with its gradually increasing diameter serves to feed and screen the material 60 until its relatively finer particles pass to the supplemental screen elements while its coarser particles are delivered from its larger end in any suitable manner. The material which is passing to the screening elements 65 3 and 4 is divided as desired by adjustment

of the gate 7 and after passing from such gate falls onto the screen 12 over which it gravitates. The finer particles separated by the screen 12 drop to the bottom of chute 11 while the tailings are delivered at the lower 70 end of the screen. The gravitation of this material is accelerated by the action of the vibrators, which serve to prevent the screens from clogging. These vibrators are continuously actuated by their cams against the tension of their springs 26 and 31. The result 75 is that both the bottom 11 and the screens 12 are vibrated through downwardly directed blows of the head pieces or hammers 22 upon the anvils 37. At the same time, the cover 80 13 is unencumbered and may be lifted with great ease for cleaning of the screening elements which, in cold weather may be required once a day or oftener when operating on clay or other plastic material. It will be 85 understood that other screens may be utilized in addition to the screen 12 and that my improvement will still be applicable thereto. It will also be understood that only one of the screening elements need be used and that 90 the other screening element may be removed or may be disconnected by the gate 7.

One of the important features of my invention is illustrated by a reference to that type of machine wherein superposed scalping and fine screens are fed by a rotating screw. My device is an improvement upon this in the sense that it accomplishes by two elements what the other device accomplishes by three. The rotating screen in question 100 not only serves to feed the material but has a screening action upon it equivalent to the screening action of the normal scalping screen and, furthermore, the material being fed has no chance to choke up the rotating 105 screen because of its constant presentation of new surfaces and an inversion of the old.

Summarizing, it may be stated that I have provided a screening machine wherein the material to be screened is delivered to a rotatable scalping screen. The material passes in one end of this screen and the coarser particles thereof are delivered from the other end, this being brought about by the gravitation of the material from the smaller end to 110 the larger end of the screen. The result is that the scalping screen serves very effectively as a feeding device and is, nevertheless, in such a position that the finer screens of the machine are readily accessible for 115 cleaning. It will be noted that my device is such that each rotatable scalping screen feeds a plurality of screens, this feeding action being regulated by a gate valve. In addition, the vibrating mechanism is such 120 that the finer screens are subjected to a series of percussive blows upon their upper surfaces while the operating mechanism for these vibrators is below the screening machine, leaving the cover of the screening machine 125 130

unencumbered by weighty parts. These are some of the principal features of my invention and they, in conjunction with other features, will be set forth in the appended 5 claims.

Having thus described my invention, what I claim is:

1. Screening apparatus comprising a screen, means for percussively vibrating said 10 screen by blows upon the upper surface thereof, and mechanisms for operating said means by apparatus beneath said screen.

2. Screening apparatus comprising a screen, a cover for said screen, means for 15 percussively vibrating said screen by blows upon its upper surface, a mechanism for operating said vibrating means, said cover being independently mounted.

3. Screening apparatus comprising a 20 chute, a screen in said chute, a cover for said chute, percussive vibrators for hammering said screen from above, said cover being capable of elevation without said vibrators.

4. In screening apparatus, a chute, a 25 screen, mechanisms for imparting vibrating movements to the wire-cloth screen by light rapid impact blows upon the upper side of the screen, and means underneath the bottom of the fines chute for operating said 30 mechanism.

5. In screening apparatus, a chute, a screen, and a cover for said chute, multiple rods having caps on their upper ends and extending through the chute, screen and 35 cover, anvils connected to said screen and chute for transmission of hammer blows from said caps, and means for rapidly reciprocating said rods.

6. In screening apparatus, a screen, multiple rods extending through said screen, hammer caps on said rods, and operating cams contacting with lower end of said rods, an anvil element connected to said screens to receive and transmit successive blows 45 from said hammer caps.

7. In screening apparatus, a screen, multiple hammer rods extending through said

screens, hammer caps on said rods, a socket coupling on lower end of each of said rods, a coil spring around each rod and supported 50 in each socket of each coupling, a short rod extending below said coupling, a roller upon the lower end of each short rod, and rotating cams coöperating with said rollers to successively lift and drop said rods, the 55 movement of the rods compressing the springs, the release of which helps to bring the rod back to its normal position.

8. In screening apparatus, a chute, a screen, a cover, rods with caps on their 60 upper ends and extending through the cover chute and screen of the apparatus, a coupling on the lower end of each rod, said couplings having sockets for the reception of coil springs, coil springs embracing 65 said rods and resting in said coupling sockets, said coil springs pressing against the under side of said chute, a short rod extending into said coupling and connected thereby to said first rod, rotating cams operative 70 to lift said rods against said coil springs, pipe casings around said rods in two sections, the upper section of the bottom secured to the upper side of the screen, said upper section having an annulus filled with 75 wood to serve as an anvil, the lower section of said pipe casing being fastened at its lower end to the upper side of the chute, an annulus upon the upper end of said lower section and forming a spring socket, a 80 spring in said last socket coiled around the casing and pressing at its upper end against the bottom side of said screen, the movement of the spring under the impact blows of the hammer on the anvil connected to the 85 screen by the casing serving to accelerate the vibration of the screen.

In testimony whereof I hereby affix my signature.

WILLARD D. RICHARDSON.
